UNITED STATES PATENT OFFICE.

LEWIS M. ELLISON, OF CHICAGO, ILLINOIS.

DRAFT-GAGE.

1,262,761.

Specification of Letters Patent. Patented Apr. 16, 1918.

Application filed February 2, 1917. Serial No. 146,096.

To all whom it may concern:

Be it known that I, LEWIS M. ELLISON, a citizen of the United States, and resident of Chicago, county of Cook, and State of Illinois, have invented certain new and useful Improvements in Draft-Gages, of which the following is a specification and which are illustrated in the accompanying drawings, forming a part thereof.

10 The invention relates to draft gages and has for its object to provide an instrument for this purpose which is of improved construction particularly with a view to securing greater convenience in use and to reducing the liability to injury in service. The invention is exemplified in the structure to be hereinafter described and which is illustrated in the accompanying drawings, wherein—

20 Figure 1 is a vertical sectional view, the plane of the section being indicated by the line 1—1 on Fig. 2,

Fig. 2 is a front elevation,

Fig. 3 is a side elevation with the attaching lugs and a detail of the supporting part shown in section,

Fig. 4 is similar to a detail of Fig. 3, but shows a different form of attaching device, and

30 Fig. 5 is a sectional view taken on the line 5—5 of Fig. 2.

The features of improvement are illustrated in connection with a scale tube generally designated 10, made in the form of a 35 U and having a bulb 11 at the upper end of one of the legs, as 12, of the U. The other leg, as 13, hereinafter referred to as outer leg of the U tube 10, is extended in front of a graduated scale 14. Preferably the tube 40 10 and the scale 14 are inclosed within a metal case 15 to which a glass front 16 is applied.

In carrying out the invention the U tube 10 is constructed to permit of the scale 14 and the associated part of the tube being located close behind the glass front 16 of the case, without requiring the case to be of great depth. The indications upon the scale 14 are thus more readily observed and when 50 pointers, as 17 and 18, are placed over the glass front 16, the importance of taking the reading from directly in front of the scale and from the exact level of the pointers, is reduced. As shown, the bulb 11 is of an up- 55 right cylindrical form and the axis of the bulb is sufficiently offset from the line of the

outer leg 13 of the U to be located a substantial distance in rear of the plane of the scale 14. In order that the chamber of the case 15 may be of reduced depth in all parts, except that part which incloses the bulb 11, the inner leg, as 12, of the U tube 10 is preferably located at the same distance from the glass front 16 as the outer leg 13. This is readily brought about by providing an elbow 19 for connecting the upper end of the inner leg 12 of the tube with the bulb 11, the connection being thereby made with the front wall of the bulb 11 adjacent its lower end.

In the usual operation of the device when made in the form shown, the chamber of the bulb 11 should be open to the atmosphere. Under these circumstances it is desirable to prevent the entrance of dust into the bulb chamber. As shown, the case 15 is formed 70 with a socket 20 at its upper end to receive the top of the bulb 11 and the rim of the bulb is firmly held within the socket 20 by a cement packing 21.

For the purpose of venting the chamber 30 of the bulb 11 without permitting the entrance of dust, the end wall of the socket 20 is formed with a tubular nipple 22, and a vented dust cap, generally designated 23, and having a threaded stem 50 is applied to 85 this nipple. As shown, the upper end of the dust cap 23 is formed with a chamber 24 and a tube 25 rises into this chamber, the bore of the tube being extended through the stem 50 of the dust cap to communicate with the bore of the nipple 22. The chamber 24 is closed at the top by a removable solid cover 26, but an opening 27 is provided in the side wall of the chamber at its lower end. It follows from this construction that if a suitable 90 dust filter is provided in the chamber 24, as by filling the said chamber with a loose packing of cotton, or the like, (not shown) the chamber of the bulb 11 will be vented but dust will be excluded. Preferably a 100 screen 28 is extended across the chamber 24 above the opening 27 to support the said packing.

In order that the U tube 10 may be connected with the part to be tested, the upper 105 end of the outer leg 13 of the tube is also extended into a socket provided in the end wall of the case 15, as at 29 (Fig. 2). In this instance, a tubular plug 30 is applied to the socket 29 over the corresponding end 110 of the U tube. Preferably the plug 30 is formed with a laterally extended nipple 31

and with a removable cover 32. In use, the laterally extended nipple 31 is connected with the part to be tested, as by the application of a flexible tube (not shown) to the 5 nipple 33. The removable cover 32 is provided upon the plug 30 for the purpose of permitting the adjacent end of the U tube 10 to be opened to the atmosphere when the valve 34 is closed. In the particular arrangement shown this is accomplished without 10 completely removing the cover 32. To this end, the cover 32 has a tubular stem 35 and this stem is formed with a lateral opening 36 near the base of the stem. If, now, a gas- 15 ket, as 37, be applied to the cover 32 at the base of the stem 35, the chamber of the plug 30 will be sealed when the cover is closed while turning back the cover will serve to 20 open the chamber of the plug 30 to the atmosphere without completely removing the cover.

As the U tube 10 and bulb 11 are formed of glass and are firmly connected with the walls of the case, it is important that the 25 case 15 should not be strained at any time, as when the gage is applied to a support, as 30. For this reason it has been found desirable that the case should be firmly clamped to the supporting surface at only a single 35 point. Under these circumstances inequalities of the supporting surface have no effect to strain the case and break the contained glass parts. As shown, the case 15 is formed with one attaching lug, as 39, which is to be 40 firmly applied to the supporting surface, the remaining lug, as 40, being merely a guiding lug not extending to the plane of the foot of the attaching lug 39. It follows that if the supporting surface, as 38, is perfectly 45 true the guiding lug 40 will be spaced apart from said surface, as at 41 (Fig. 3).

In applying the instrument to the supporting surface, as 38, an attaching screw, as 42, is inserted through the supporting lug 39 45 and used for firmly clamping the said lug against the supporting surface. It is, therefore, not important that the attaching screw 42 make a snug fit in the opening, as 43, of the lug 39. The opening 43 accordingly is 50 slotted to permit of adjusting the case to an upright position after the insertion of the attaching screw. The attaching screw, as 44 (Fig. 3) or 45 (Fig. 4) which is inserted through the guiding lug 40, on the other 55 hand, has no clamping effect upon this lug. The screw 44 or 45 should accordingly make only a guiding fit in the opening 46 through the lug 40 and provision is made for preventing the screw 44 or 45 being inserted 60 far enough for the head of the screw to engage the lug. When a machine screw, as 44, is employed, the insertion of the screw is limited by correspondingly limiting the length of its screw thread, as 47. When a 65 wood screw, as 45, is employed, the inser-

tion of the screw is conveniently limited by the use of a bushing. This bushing may take the form of a piece of metal tube, as 48, mounted upon the stem of the screw. In either case, the walls of the opening 46 70 through the lug 40 should be cupped at one side of the lug, as at 49, to prevent binding upon the stem of the screw 44 or upon the bushing 48, in event the inequalities of the surface 38 are such that the axis of the screw 75 44 or 45 is not parallel with the axis of the screw 42.

The pointers, as 17, 18, may be used for indicating the allowable variation in the 80 readings upon the scale 14 consistent with an economical operation of the furnace in connection with which the device is used. For this purpose the pointers are adjustably applied to the rim of the case 15 to extend over the glass front 16, as by being made in 85 accordance with the invention forming the subject of my patent for draft gage, No. 1,145,676 dated July 6, 1915. It is an important characteristic of the construction 90 that the outer leg 13 of the tube 10 and the scale 14 are located close under the glass front 16 and that this glass front is nevertheless flat and of rectangular shape.

I claim as my invention,—

1. In a draft gage, in combination, a scale 95 tube having an open bulb at one end, a casing inclosing the bulb and scale tube, the wall of the casing having a socket into which the rim of the bulb is fitted and the end wall of the said socket being apertured, a cap 100 applied to the aperture in the end wall of the said socket, the said cap being chambered to receive a dust filter and the chamber of the cap being vented adjacent its lower end, and a tube rising within the cap 105 chamber, the bore of the last mentioned tube being continued through the floor of the cap chamber to communicate with the chamber of the bulb.

2. In combination, a cap having a chamber 110 to receive a dust filter and a tubular stem for entering the nipple of a draft gage, the cap chamber being vented adjacent its lower end, a tube rising within the chamber 115 of the cap, the bore of the tube communicating with the bore of the stem, and a removable imperforate cover for the chamber of the cap.

3. In a draft gage, in combination, a chambered casing, a scale tube mounted 120 within the chamber of the casing, the ends of the tube being held in the walls of the casing, a pair of apertured lugs formed on the casing walls, one of the lugs having a contact face for engagement with the face 125 of a support and the other lug being located entirely in front of the plane of the said contact face, a clamping screw passing through the aperture of the lug having the contact face for engagement with the sup- 130

port and a pin positioned on the support and entering the aperture of the other lug.

4. In a draft gage, in combination, a chambered casing having a flat glass front, 5 a scale tube and connected bulb mounted within the chamber of the casing, and housed thereby, a part of the scale tube adjacent the bulb being transverse to the axis of the bulb and the body of the scale tube being for- 10 wardly offset from the axis of the bulb to extend adjacent the glass front of the casing.

5. In a draft gage, in combination, a chambered casing having a flat glass front

and the chamber of the casing being of un-
uniform width from front to rear, the rear 15
wall of the narrower part of the chamber
being flat, a scale marked upon the said flat
part of the rear wall of the chamber and a
tube and connected bulb mounted within
the chamber of the casing and housed there-
by, the bulb fitting the wider part of the
chamber and the tube being offset from the
axis of the bulb and extending in front of
the said scale.

LEWIS M. ELLISON.
